UNITED STATES PATENT OFFICE.

FERDINAND SCHOETTLE, OF PHILADELPHIA, PENNSYLVANIA.

IMPROVEMENT IN SHEARS.

Specification forming part of Letters Patent No. 122,333, dated January 2, 1872.

SPECIFICATION.

I, FERDINAND SCHOETTLE, of the city and county of Philadelphia and State of Pennsylvania, have invented certain Improvements in Stationary Shears for cutting paper, paste-board, and other light material, of which the following is a specification:

My invention relates to an improvement in the shears used by paper-box makers and others; and consists of a lengthened adjustable journal-box in combination with a tightening-bolt or journal.

On reference to the accompanying sheet of drawing, Figure 1 is a side view, showing the shears, journal-box, and tightening-bolt. Figs. 2 are side and end views of the adjustable journal-box. Fig. 3 is a top view of Fig. 1. Fig. 4 is a section through the journal-box, upper knife, and the tightening-bolt. Fig. 5 is a view of the tightening-bolts and nuts.

General Description.

A and B are the top and bottom knives of a pair of shears. The bottom one, B, is attached in the usual manner to a table or stand. C is an adjustable journal-box, which is secured to the frame E of the table by bolts passing through vertical slots b b' in the butting piece of the box. B is a bolt or journal which turns in the box C. Its inner end a'' is reduced in diameter to correspond with the opening in the eye or swell of the upper knife A, so that when the nut a is screwed up the knife is firmly pressed against the shoulder formed by the reduction in the diameter of the bolt. The outer end of the bolt D is shorter than the adjustable journal-box C, to provide for the wear of the eye of the knife A and the end of the box

C against each other. The nut a secures the knife A to the bolt D. The nut a' on the opposite end of the bolt keeps it from working out of its journal and also serves to take up all lost motion of the knife A, and thereby prevent it from wobbling. The nut a'' is a set-nut, to keep the nut a' from loosening or backing off while the bolt D is turning. The adjustable journal C can have more or less shear given to it by means of the vertical slots b b'. Simply backing or loosening its bolts enables it to be raised or lowered to any required degree at will, in which consists its adjustability. The upper knife A or its lever has its boss or eye of the same diameter as the end of the journal-box C against which it works. Its action is entirely distinct from that of the lower knife B. It turns with the pin D as a center, while the knife B is stationary on the table.

The pin D turns or rocks in the journal-box C, and, as before mentioned, its larger diameter is shorter than the box C, whereby, by means of the nuts a a'', the knife A can be nicely adjusted, and all lost motion caused by the wear and tear of the eye against the end of the box taken up.

I claim as my invention—

The upper knife or lever A, the adjustable journal-box C, and the bolt or journal D, when constructed, arranged, and operated as shown and described.

In testimony whereof I hereunto sign my name.

FERDINAND SCHOETTLE.
